TRAIN DETECTING AND REPORTING APPARATUS

Willard P. Place, Wilkinsburg, Pa., assignor to
The Union Switch & Signal Company, Swiss-
vale, Pa., a corporation of Pennsylvania

Application June 5, 1941, Serial No. 396,732

5 Claims. (Cl. 246—122)

My invention relates to train detecting and reporting apparatus, and it has particular reference to the organization of such apparatus into novel and improved means for detecting the movement of complete and intact trains past a selected location in a trackway. More particularly, my invention relates to the provision of train detecting apparatus of the type adapted for use in connection with manual block or other non-track-circuited stretches of track for detecting and reporting the movements of trains past unattended block stations.

In manual block territories where continuous track circuits are not employed, the signalmen at the various block stations are required to observe all passing trains and note that they are complete and in order, and that the marker signals required by the rules are properly displayed. Should a train without markers pass a block station, the signalman at such station is required to notify the signalmen at the next block station in each direction, and must not report that a train is clear of the block or unlock the next block in the rear unless he has ascertained by observing the train markers that the train is complete.

At an unattended block station where signals are manually controlled from a central office by means of a communication or remote control system, suitable train detecting apparatus, usually of the type involving a detector track circuit, may be employed as a tripping means to set the associated signals at stop and also to cause an indication to be transmitted over the communication system to the office to indicate the presence of a train, as is well known. When a train passes the train detecting apparatus, for example, the remote control system may be conditioned to OS the train, that is, to transmit an indication reporting its movement past the block station to the control office. Neither a track circuit, nor other known train detecting apparatus, such as a light beam, photo-cell combination, however, is effective to detect whether or not the train is intact, hence such an OS indication might be transmitted to the office when only a portion of a train passes the detector apparatus. An operator relying upon the OS indication received from a block station location and assuming that the complete train has passed that point, might therefore signal other traffic through the block whereas in fact a portion of the first train may be in the block and thus constitute a hazard to the other traffic.

In view of the above-mentioned and other im-

portant considerations, it is an object of my invention to provide novel and improved means for detecting and reporting the passage of an entire and complete train.

5 Another object is to provide novel and improved means adapted for use with remote control or centralized traffic control systems applied to non-track-circuited stretches of track, for detecting the passage of complete and intact trains.

10 An additional object is to provide novel and improved apparatus in the wayside cooperating with means on a train for detecting energy applied by the train to the track rails.

15 A further object is to provide novel and improved means on a train for applying energy to the rails of a stretch.

20 Another object is to provide a novel and improved axle driven generator on a vehicle for generating impulses of electrical energy having a strength or magnitude independent of the speed of the vehicle.

25 The above-mentioned and other important objects and characteristic features of my invention which will become readily apparent from the following description, are attained in accordance with my invention by applying electrical energy from a train to the rails of a stretch, and by utilizing means in the wayside for detecting and reporting to a remote office the presence of such energy.

30 The invention further provides a novel and improved form of axle driven generator capable of generating impulses of energy having a substantially constant magnitude regardless of train speed, and novel and improved wayside means for detecting at a selected point in the trackway the presence of energy applied by the train to the rails.

35 40 I shall describe one form of apparatus embodying my invention, and shall then point out the novel features thereof in claims.

45 The accompanying drawing is a diagrammatic view illustrating one form of apparatus embodying my invention.

50 Referring to the drawing, the reference characters 1 and 1a designate the track rails of a stretch of track such as a manual block, which usually is not provided with continuous track circuits. The rails 1 and 1a are divided by insulated joints 2 into a track section a—b, which may be of any convenient length preferably longer than the distance between the trucks of any vehicle operating thereover, and may for example have a length of the order of 60 feet.

Section *a*—*b* is provided in the usual manner with a normally energized train shuntable track circuit comprising a suitable source of current, such as a battery 3, and a track relay TR, connected to the rails at opposite ends of the section, respectively. Relay TR has connected across its terminals a resistor 4, while resistors 5 and 6 are interposed one in each lead of the battery to the track rails. The section also is provided with wayside apparatus for detecting the presence of energy applied from a vehicle to the rails of the section. This apparatus includes a loop circuit formed by connecting a conductor 7 between a center tap of battery 3 and a mid terminal tap of resistor 4. The loop circuit thus formed includes the track rails 1 and 1a in multiple, and also includes a primary winding 8 of a transformer 9 interposed in conductor 7. In addition, the wayside apparatus includes relay means comprising a relay CR and an electronic tube of the controlled ionization type such as, for example, a grid controlled gaseous discharge tube 11 of the hot cathode type. The heater element 12 of tube 11 is provided with an obvious energizing circuit supplied when back contact 14 of relay TR is closed, with unidirectional energy from a suitable source, such as a battery not shown but having its opposite terminals designated by the reference characters B and C. Relay CR is interposed in the plate circuit of the tube, which circuit extends from terminal B through back contact 15 of relay TR, the winding of relay CR, plate 16, intervening tube space and cathode 17 to terminal C. The potential established across the plate and cathode of tube 11 when back contact 15 of relay TR is closed, is selected to be below the breakdown potential of the gas medium, hence tube 11 remains non-conducting until such time as winding 10 of transformer 9 connected across the cathode and grid 18 of the tube, establishes a potential sufficient to permit the ionization of the gaseous medium. When this happens, the tube becomes conducting and remains so regardless of the grid potential, until the plate circuit is interrupted.

Relay CR has associated therewith and controls suitable means for transmitting information from the trackway location to a remote office, which may, for example, be a dispatcher's office. This information may, for example, be transmitted over a communication or centralized traffic control system of the type shown in the Lewis Patent No. 2,297,130, granted on April 16, 1940, for Remote control apparatus, or as represented, over a line circuit extending from section *a*—*b* to an indicator 20 at the remote office.

The wayside apparatus is in its normal condition, as represented in the drawing, when section *a*—*b* is unoccupied. In this normal condition of the apparatus, relay TR is picked up and both the heater and plate circuits of tube 11 are open at back contacts 14 and 15 of relay TR, respectively. Relay CR is deenergized and holds open its front contact 19 to open the previously mentioned circuit over which indicator 20 is controlled.

The wayside apparatus is arranged to pick up relay CR and cause indicator 20 at the remote station to become active, only when energy is applied by a train or vehicle to the track rails. A vehicle V is represented in the drawing as being provided with means for applying energy to the rails of the section, and as shown such means comprises a source of energy having its opposite terminals connected one to each truck of the ve-

hicle through wires 35 and 36, respectively. The trucks are insulated from each other, hence the source applies energy to the track rails through the medium of the trucks, axles and wheels, and causes current to flow through the rails between the two sets of trucks.

The source of energy on the vehicle may comprise a battery or a generator, but I prefer to use a novel form of axle driven generator capable of generating impulses having a substantially uniform magnitude independent of the vehicle speed. This generator comprises a cam 22, either secured to one of the axles of the vehicle, or driven by the axle through a mechanical connection indicated by a dotted line in the drawing; a mechanical linkage comprising arm 23, link 24, springs 25 and 26; and an armature 27 of an impulse generator comprising a permanent magnet 28, confronting bifurcated or U-shaped pole pieces 29, and coils 30. Arm 23 is pivotally secured at 31 preferably to the frame of the vehicle, and actuates armature 27 through the medium of link 24, pinned at one end to arm 23 and at the other end to armature 27. Spring 26, operating in a sleeve 33, is interposed in the mechanical link member 24, while spring 25 biases arm 23. Armature 27 is pivoted at 32 about its center for movement from a position shown where it engages diagonally opposite legs of the pole pieces 29, to another position indicated in dotted lines in the drawing and in which the other pair of diagonally opposite legs of pole pieces 29 are energized. The armature is held by magnetic attraction in its last operated position by the flux due to magnet 28 threading pole pieces 29 and armature 27, and the armature functions to provide a path of low reluctance between the pole pieces.

When cam 22 rotates to the position shown and actuates arm 23 against its spring bias, armature 27 occupies the position represented and flux threads the armature and coils 30 in one direction. Continued rotation of cam 22 permits arm 23 to be actuated by spring 25 to its biased position, and arm 24 then compresses spring 26 until it exerts enough force on armature 27 to flip or cause the armature to operate abruptly, against the magnetic attraction of magnet 28, to its other (dotted) position wherein the direction of flux in the armature and coils is reversed, thus inducing in the coils 30 an electromotive force which is applied to the track rails through the wheels of the vehicle. Further operation of cam 22 back to its illustrated position causes the extension of spring 26 until it exerts sufficient force on armature 27 to again flip or operate abruptly the armature, against the magnetic effect of magnet 28, to its illustrated position, thereupon again reversing the direction of flux in the armature and coils 30 and inducing in the coils an electromotive force which also is applied to the track rails.

Each change in position of the armature reverses the direction of magnetic flux through the armature 27 and coils 30, thus causing each successive two induced voltage impulses impressed on the track rails through wires 35 and 36 and the trucks, to have opposite polarities. The frequency of these impulses is of course dependent upon the speed of the vehicle, but the strength or magnitude of the impulses is not affected by the vehicle speed since the time required for operation of the armature from one position to the other remains substantially constant.

In accordance with my invention, it is contemplated that a vehicle, such as V, equipped with

the train-carried apparatus of the type just described, will be placed at the rear of each train, thus enabling operation of the wayside apparatus hereinbefore described by such train-carried apparatus to be utilized to provide means for OS'ing complete and intact trains at a remote office. For example, the vehicle V may be a caboose placed, as is the custom, at the rear of a freight train. When the train proceeds along the stretch and enters section *a*—*b*, relay TR is shunted, heating element 12 of tube 11 is energized, and a potential is established across the plate and cathode of the tube. The tube, however, remains non-conducting until the caboose enters the section and the source carried thereon impresses on the track rails of section *a*—*b* a voltage which appears between the two insulated trucks of the caboose. This voltage is also impressed across the loop circuit including conductor 7 and winding 8 of transformer 9. The complete loop circuit may be traced from the one or right-hand truck (as viewed in the drawing) of the caboose through the rails 1 and 1a in multiple, the connections of relay TR with the track rails, resistor 4 to its mid-point connection, conductor 7, winding 8 of transformer 9, the center tap of battery 3, the two portions of battery 3 and resistors 5 and 6 respectively, and the two track rails 1 and 1a in multiple to the other or left-hand truck of the caboose. This loop circuit path is, of course, connected in multiple with the path which extends through the track rails between the two trucks of the caboose, and a portion of the voltage impressed across these two paths in multiple appears across winding 8 and induces in winding 10 a voltage which causes tube 11 to become ionized and conducting. The voltage will of course be induced in winding 10 as long as both trucks of the caboose are within section *a*—*b* to cause a voltage to be impressed on the rails of that section, but since tube 11 becomes ionized when the voltage is first induced in winding 10, the continued induction of a voltage in winding 10 has little if any effect upon the operation of the apparatus. The ionization of tube 11 results, however, in the energization of relay CR which accordingly picks up to close its front contact 19, and indicator 20 at the remote office becomes energized to indicate that energy is present in section *a*—*b* due to a vehicle, equipped with energy applying means, occupying the section. The operator at the office is, therefore, assured that when indicator 20 becomes illuminated, the train passing the remote location is complete and intact. Should a train part and break in two, and only the forward portion pass through section *a*—*b*, the tube 11 would not become conducting and hence no OS would be sent to the remote office. In such an event, the operator would consider the block occupied and this would, of course, be the case since the second portion of the train has not cleared the block. It follows, therefore, that my invention provides means for OS'ing complete and intact trains in territories where continuous track circuits are not employed, and that it involves apparatus arranged so as to assure the operator that when an OS indication is received, the entire train has passed the location and there is no danger of a portion of such train impeding the movement of other traffic through the block.

After a train which includes a vehicle V equipped to supply energy to the track rails, passes section *a*—*b*, the track relay TR picks up to open both the plate and filament circuit of tube

11, whereupon both relay CR and indicator 20 at the office station become deenergized, and the apparatus is restored to its normal condition as represented in the drawing.

5 Although I have herein shown and described only one form of train detecting and reporting apparatus embodying my invention, it is understood that various changes and modifications may be made therein within the scope of the appended claims without departing from the spirit and scope of my invention.

Having thus described my invention, what I claim is:

15 1. Means for detecting and reporting the passage of the rear of a train, comprising in combination, a stretch of railway track having an insulated section provided with a track circuit including a track relay, a loop circuit for said section including the rails thereof in multiple, a train to travel said stretch, means on the rear vehicle of said train for impressing energy on the rails of said section, an electronic relay in the wayside having a plate circuit controlled by said track relay and having a grid circuit responsive to energy impressed by said train on said loop circuit, and means controlled by said relay for reporting the presence of energy in said loop circuit to a remote office or station.

20 2. In combination with a stretch of railway track having an insulated section provided with a track circuit including a track relay, a loop circuit for said section including the rails thereof in multiple, an electronic relay of the controlled ionization type having its grid circuit coupled to said loop circuit and having a plate circuit controlled by said track relay, a train to travel said stretch, means carried on said train for impressing energy on the rails of said stretch, and means in the wayside of said stretch controlled by the plate circuit of said tube and rendered effective only in response to energy applied by said train carried means to said loop circuit.

25 3. In combination, a stretch of railway track having an insulated section provided with a track circuit including a track relay, a loop circuit for said section including the rails thereof in multiple, an electronic tube of the controlled ionization type, a plate circuit for said tube controlled by said track relay, means coupling the grid of said tube to said loop circuit for causing current to flow in the plate circuit of said tube in response to energy in said loop circuit, a train to travel said stretch, means carried on the rear of said train for applying electrical energy to the rails of said stretch, and means at a remote point controlled by energy passed by said tube when conducting for indicating the presence of energy in said loop circuit.

30 4. In combination, a stretch of railway track having an insulated section provided with a normally closed circuit track circuit including a track relay, a loop circuit for said section including the rails thereof in multiple, an electron tube of the controlled ionization type having a plate circuit controlled by said track relay and a grid circuit receiving energy from said loop circuit, a train to travel said track, means on said train for applying electrical energy to the rails of said stretch, and means at a remote point responsive to energy passed by said tube when said relay is released and energy is applied by said train on said loop circuit.

35 5. A system for OS'ing trains at an unattended location, comprising in combination, a stretch of railway track having at a selected location an in-

sulated section provided with a normally closed track circuit including a track relay, a loop circuit for said section including the rails thereof in multiple, an electron tube of the controlled ionization type having a plate circuit controlled by said track relay and a grid circuit receiving energy from said loop circuit, a train to travel said

track, means on the rear vehicle of said train for applying energy to the rails of said stretch, and means responsive to energy caused to flow through said tube for reporting at a point remote from said 5. location the passage of a train having said energy applying means.

WILLARD P. PLACE.
